UNITED STATES PATENT OFFICE.

JAMES F. HOXSEY, OF WASHINGTON, DISTRICT OF COLUMBIA.

MOLD AND LINER.

1,079,049.

Specification of Letters Patent. Patented Nov. 18, 1913.

Application filed February 11, 1913. Serial No. 747,616.

To all whom it may concern:

Be it known that I, JAMES F. HOXSEY, a citizen of the United States, residing at Washington, in the District of Columbia, have invented new and useful Improvements 5 in a Mold and Liner, of which the following is a specification.

This invention relates to an improvement in molds for line casting machines, and has 10 for its principal object to simplify the manufacture and use of that type in which the length and thickness of the line is limited by the thickness and spacing of liners removably engaged between permanent relatively 15 adjustable side elements. It is an important object to effect an improvement over the form of mold and liner illustrated in my co-pending application No. 732,671, filed Nov. 21, 1912. Owing to the extreme requirements of accuracy in the matter of measurements and fitting of parts in such devices, 20 every variation from a simple form (a parallelopiped) is an added detail of expense and liability of inaccuracy in the formation 25 of dies and the parts of the device, involving more extended labor and inspection, and perhaps weakening the parts and affecting detrimentally their operation. It is therefore an important attainment of my invention 30 that it permits the formation of all parts requiring to be moved or interchanged for the modulation of the size of the mold from simple blanks of a common thickness with that of the slugs to be formed therewith, resulting 35 at the same time all the advantages of the type of liner illustrated in the above named application. It is made possible to use one constant element of the liner upon which the movable element is adjustably secured, 40 for all lengths and thicknesses of slugs. Access of type metal to the front of the mold is obviated without complicating the form of the movable member of the liner, or the constant member. An important end attained 45 is the formation of a liner including a stationary element and a movable element adapted to be secured thereon against longitudinal movement, the means for securing the movable member being entirely without 50 the major or maximum length of the casting space, requiring but three sizes of the mov-

able member for the full range of adjustment from five picas to thirty, but still applicable to the present size of and type of mold wheel as used in the Mengenthaler 55 linotype machine without modifying its general construction, or detriment to its strength or operation.

Additional objects and advantages will be apparent, some of which will appear from 60 the following description and from the drawings, in which—

Figure 1 is a perspective view of the upper part of the base of the mold, Fig. 2 is a similar view with the constant in place, 65 Fig. 3 is a front view of the mold with the constant in place, Fig. 4 is a top view of the mold with the constant and spacer in initial position, Fig. 5 is a similar view showing the spacer at the inner limit of its adjustment, Fig. 6 is a top view of the constant detached, Fig. 6^a is a top view of a rectangular plate employed with the constant, Fig. 7 is a bottom view of the constant, Fig. 8 is a 70 bottom view of the first spacer, Fig. 9 is a 75 similar view of the second spacer, Fig. 10 is a similar view of the third spacer, Fig. 11 is an inner end view of the mold base with constant and spacer in place, Fig. 12 is a perspective view of a mold cap constructed 80 for use with the modified form of the device, Fig. 13 is a similar view of a portion of the mold base and a modified constant element adjusted thereon, Fig. 14 is a fragmentary 85 front view of the mold having the modified form of my device included therein, and having the smaller spacer at the inner limit of its adjustment.

There is illustrated a mold base 10 of a mold of the linotype class, but differing in 90 having the top at the left hand end cut away as at 11, forming a step, the channel 12 being formed intermediately thereof extending transversely of the base. The top of the step is about six points, printers' measure, below 95 the mold face 13 of the base, and the channel 12 is of similar depth in the step, although these measurements are not arbitrary, and may be increased without detriment. The inner termination of the step 11, indicated 100 at 14 is located just without the maximum length of the casting space of the mold when

assembled. A check screw 15 is engaged in the step outwardly of the channel 12 and intermediately of the front and back of the mold, for a purpose to be explained. The base 10 may otherwise be formed as at present or otherwise for engagement in a mold wheel of the type of the linotype, although it is not necessarily limited to that class of machine. It is used as shown in co-operation with a mold cap plate (not illustrated) and stationary right hand liner 16 both of the form now employed generally.

Fixed removably on the left hand end of the base 10 there is a liner constant element 19 adapted to fit upon the step 11 with its major upper face 17 flush with the surface 13 of the base; having a rib 18 fitting snugly in the channel 12, and an extension 20 approximately one-half the depth of the base 10 from front to rear projecting beyond the left hand end of the base. The rear side of the constant is thus much shorter than the front, and in face stops short of the end of the base 10, so that the constant may slide freely inward until the screw 15 engages against the inner side of the extension 20, it being the function of the screw to check the constant against inward movement when flush with the front and rear sides of the base. A removable rectangular plate or block 21 is carried on the upper side of the constant, this plate at its left and rear lying flush with the corresponding edges of the constant, its front edge being alined with the rear edge of the extension 20, and its right hand edge being spaced inwardly on the constant from the corresponding edge of the latter. It is provided with a small notch 22 on its right hand edge not opening on the under side of the plate, but inclining inwardly into the upper side. This plate may be secured in place in any desirable manner, that shown involving two pins 23 carried by the plate on its underside and engaging in correspondingly spaced recesses in the constant. The thickness of this plate corresponds to the thickness of the slug to be cast, as should the thickness of the right hand liner 16. A channel 25 is formed centrally of the extension 20 and extending longitudinally of the constant, having opposed scallops 26 in its edges spaced one nonpareil or six points apart.

A spacer member 27, is provided, shaped and adapted to lie snugly on the constant, being of the shape of the letter L and of the same thickness as the plate 21 throughout. The spaced member includes a short arm 28 the length of which corresponds to the depth 60 of the mold, and a long arm 29 at right angles to the first, and having a cylindrically headed screw 30 on its under side near the outer end adapted to fit snugly between any two opposed scallops of the channel 25. The

arm 29 is of a breadth corresponding to the 65 distance between the front side of the plate 21 and the front side of the mold, and the short arm is of about the same width. The inner left hand corner of the long arm of the spacer is curved concentrically with the screw 70 30 so that it will be free for outward pivotal movement of the spacer when engaged in the channel 25 adjacent the plate 21. The left side of the short arm 28 is provided with a notch 31 similar, and opposed, to that 22 75 on the plate 21. These notches have the same function as those on the corresponding elements in my preceding application before mentioned, viz: to effect binding engagement between the constant, spacer and filling of 80 type metal therebetween, as long as the mold cap and base are in operative position therewith. The right hand side of the spacer, which may be termed the mold face, 32, is provided at the inner end of the arm 28 85 with the projection 33 designed to recess the lower corner of the slug cast thereagainst. The back face 34 of the arm may be inclined inwardly from adjacent the projection 33 toward the notch 31, whereby the trimming 90 knife passing along the back side of the mold will not strike abruptly against the arm 28 in case it should project slightly beyond the mold. Under proper usage, however, the spacer will be properly checked 95 against movement too far in by engagement of the arm 29 against the plate 21. In case it should project too far in, the trimming knife, striking the inclined back face, will simply force the spacer outward to proper 100 position, without affecting detrimentally the operation of the liner or the machine.

In use, the liner may be adjusted without removal of the mold base or cap plate from the mold wheel, and these parts are manipulated in every way the same as with present construction, or as would be possible with the familiar one-piece liners now generally used. The cap plate being raised to form a space between it and the base 110 slightly greater than the thickness of the slug to be cast, a right hand liner 16 is adjusted in place, and a plate 21 of proper thickness adjusted upon the constant 19, after which the spacer 27 is positioned on 115 the constant with the head of the screw 30 adjusted in the proper place in the channel 25 and the three elements presented in the left hand end of the mold and forced in until checked by the screw 15. The cap plate 120 is then forced down upon all, in the customary manner. Should it be necessary to change the length of the line, only, it is not necessary to remove the constant entirely, but after loosening the cap plate sufficiently 125 the constant is drawn out until the arm 29 of the spacer clears the front of the mold, after which the spacer may be adjusted to

the new position. The scallops in the channel 25 are virtually segments of circular recesses so closely spaced that they overlap, and if desired small circular recesses of less diameter and spaced from each other may be substituted if desired. As shown, there are seventeen of the recesses, and with the customary mold, the maximum length of slug cast in which is 30 picas, the spacer 27 will permit the shortening of the line in six-point stages to 22 picas. In order to obtain the full range of lengths needed in printing offices generally, I provide a second and a third spacer 35 and 36 respectively, the one 35 having the short arm so broadened as to form a head 37 with a mold face 32 similar to that of the spacer 27, of even thickness, the front edge adapted to lie flush with the front of the mold, and the back face tapered or inclined inwardly as desired to obviate liability of damage to the trimming knife as before mentioned. The arm 39 is similar in size and function to that 29 before described. The enlargement of the second spacer is such that with the screw 30 engaged in the outermost of the recesses of the slot channel 25, the mold face 32 is in position to limit the length of the slug to 21½ picas. Having the same manner and range of adjustment as the spacer 27, this second spacer 35 may be used to produce a slug of a minimum length of 13½ picas. The spacer 36 is similarly increased in size so that the head 40 is produced comprising nearly two-thirds the length of the spacer, and when adjusted in initial or outermost position, will limit the length of the mold space to 13 picas, and permit its limitation to a minimum of five picas. A shorter slug than this is rarely cast. In the event that adjustments are required that are not permitted by the spacing of the recesses of the channel 25 as shown, additional constants may be provided having similar channels differing in relative position thereon one or more points, as required.

It will be apparent that the simple contours of the plate 21 and the spacers will permit their manufacture at a low cost, and, together with the constant, the device requires a small amount of labor and few machine operations in its production. The front of the mold is entirely closed thereby beyond the mold slot without requiring structural complications, and even with the smallest type, the liner parts may be made of ample strength and accuracy without difficulty.

In order to obviate the necessity for using special thicknesses of plates 21 with the different fonts or heights of type, the device is preferably constructed as shown in Figs. 12 to 14 inclusive where a slight modification

in the form of the mold cap is involved. In these views a mold cap 41 is shown, and a mold base 10' (which may be engaged in the mold wheel and the mold manipulated in substantially the same manner as now practised in the Mergenthaler Linotype). The cap is formed with a channel 42 extending from the front to the rear across the lower face at the left hand end, the channel having a vertical planiform seat surface 43 at its right side, the remainder of the slot being formed as shown or as otherwise desired, the depth here being decreased toward the left side. The mold base may be formed as before described. There is shown a threaded hole 44 in the base adjacent the left end, adapted to be engaged by the clamping screw 45 engaged through the cap, this being a familiar method of fixing the cap and base in operative position. The constant 46 here shown is also constructed exactly the same as before described with the exception of the backing block 47 (the equivalent of the plate 21), and the constant is engaged with the base and co-operative with the spacers before mentioned in the same way, described. The block 47 is located in the same relative position on the constant 46 as the plate 21 was located on the constant 19, but is preferably a permanent part of the constant. It is provided with a vertical planiform right hand side 48 adapted to abut snugly against the face 43 as in Fig. 14, with the forward side serving, as did that of the plate 21, to engage the inner sides of the arms 29 of the spacers. The height of the block at the right side is approximately 18 points, or three nonpareils, and the channel is of a corresponding depth at its inner side. The left side of the block is of less height and the block itself may be considerably narrower than the channel, conforming generally to its shape however, so that the cap and base may be adjusted in contact while the constant is in place. It is thought that the height of the block as shown is ample for the requirements of general work on such machines where the height of the line rarely exceeds 14 points. Fig. 14 discloses a mold adjusted to cast a slug having a height of twelve points, the spacer 27 being at the inner limit of its adjustment. It will be seen that by the use of this construction the left end of the mold slot behind the arms 29 of the spacers will always be closed throughout the vertical adjustment of the cap within the limit of the height of the block 47.

What is claimed is:

1. A mold of the type described for slug casting machines including a base having a plane mold face and being offset at one end without the casting space, a constant element engaged in said offset having a plane

face flush and aligned with said mold face, and being slidably removable from the front of the mold, a block carried by the constant at its inner side, a liner detachably engaged with the mold at the end opposite the constant, a longitudinally adjustable spacer corresponding in thickness with the liner and adapted to abut said block throughout its adjustment, and means coöperative between the constant and spacer to hold the latter against longitudinal movement and freely for lateral outward movement from the mold.

2. A mold for line casting typesetting machines of the type described including a base having a plane mold face and an offset face at one end without the casting space, a constant element engaged in said offset having a plane face flush with and aligned with the said mold face, and being slidably removable from the front of the mold, a block carried by the constant at its inner side, a liner detachably engaged with the mold at the end opposite the constant, an adjustable spacer corresponding in thickness with the liner and adapted to abut said block when in operative position, and means coöperative between the constant and spacer to hold the latter against longitudinal movement.

3. A mold of the type described including a base having a plane mold face and an offset at one end without the casting space, a constant element engaged in said offset, having a plane face flush with and aligned with the said mold face and being slidably removable from the front of the mold, a liner backing plate carried by the constant at its rear side, a liner carried by the base at the side opposite the constant, a spacer corresponding in thickness with the liner having a portion adapted to close one end of the mold and an extension projecting before and sliding against said plate, and means coöperative between the constant and spacer to hold the latter adjustably against longitudinal movement.

4. In a mold of the class described the combination of a base having a plane mold face and an offset face at one end outwardly of the mold space, a constant element engaged in said offset slidably for removal from the front of the mold and having a plane face flush with and aligned with the said mold face, a block carried at the rear side of the constant, a spacer having a portion adapted to form one face of the mold and an extension projected before and against said block over said plane face of the constant, and means coöperative between the constant and the spacer to hold the spacer adjustably against longitudinal movement.

5. In a mold of the class described, the

combination of a mold base having a plane 65 mold face and an offset without the mold space at one end and a liner comprising a stationary element fitted in the offset of the base having an upper face flush with the said mold face, an adjustable member 70 adapted to close the adjacent end of the mold space slidable over the stationary element, and means coöperative between the elements of the liner to hold the adjustable member against longitudinal movement. 75

6. A mold of the class described comprising a cap having a lower mold face, said face terminating at one end in a seat face formed on the cap and extending above the mold space, a mold base having a mold face 80 adapted to be opposed in spaced relation to that of the cap to form a mold space, said base having an offset face without the mold space at the end adjacent the said seat face on the cap, a constant engaged in the offset 85 of the base and slidable from the front of the mold, a block carried at the rear side thereof having a vertical inner side adapted for snug abutment against the said seat face of the cap, a removable liner engaged between the cap and base opposite the constant, a spacer at the end having a portion adapted to form one face of the mold and an extension projected before and engaged 90 against said block, means coöperative between the constant and spacer to hold the spacer against longitudinal movement, and means to hold cap and base in operative position. 95

7. A mold of the class described comprising a cap, having a lower mold face, a channel being formed in the underside without the mold space extending from the rear toward the front and having a seat face at the side next the mold space, a mold base 100 having a plane mold face adapted to be opposed in spaced relation to that of the cap to form a mold space, said base having an offset face without the mold space at the end adjacent the said seat face on the cap, a constant engaged in the offset of the base and slidable from the front of the mold, a block at the rear thereof having a vertical inner side adapted for snug abutment against the said seat face of the cap, a removable liner engaged between the cap and base opposite the constant, a spacer having a portion adapted to form one face of the mold and an extension projected before and engaged against said block, means coöperative 105 between the constant and spacer to hold the spacer against longitudinal movement, and means to hold cap and base in operative position. 110

8. In a mold of the class described a cap 115 having a recess at one end having an inner transverse seat face, a base having an end closing block adapted for engagement in

the recess and having an inner face adapted for snug engagement against the seat face throughout normal relative spacing of cap and base, a right hand removable liner and 5 an intermediate adjustable liner held between the cap and base.

In testimony whereof I have hereunto

set my hand in presence of two subscribing witnesses.
